(57) **CLAIM**

The ornamental design for a lens mount, as shown and described.

DESCRIPTION

FIG. 1 is a rear, top, left perspective view of a first embodiment of a lens mount showing our new design;

FIG. 2 is a rear elevational view thereof;

FIG. 3 is a left side elevational view thereof;

FIG. 4 is a right side elevational view thereof;

FIG. 5 is a top plan view thereof; and

FIG. 6 is a bottom plan view thereof.

FIG. 7 is a front, top, right perspective view of a second embodiment of a lens mount showing our new design;

FIG. 8 is a front elevational view thereof;

FIG. 9 is a left side elevational view thereof;

FIG. 10 is a right side elevational view thereof;

FIG. 11 is a top plan view thereof; and

FIG. 12 is a bottom plan view thereof.

FIG. 13 is a rear elevational view of a third embodiment of a lens mount showing our new design;

FIG. 14 is a right side elevational view thereof;

FIG. 15 is a left side elevational view thereof;

FIG. 16 is a top plan view thereof; and,

FIG. 17 is a bottom plan view thereof.

Portions in broken lines are for illustrative purposes only and form no part of claimed design. Dot-dash broken lines define the boundaries of but not included in, the claimed design.

1 Claim, 15 Drawing Sheets
